DESIGN FOR AN ELECTRIC VIBRATORY INTERRUPTER DEVICE

William A. McNaught, Chicago, Ill., assignor to
P. R. Mallory & Co., Inc., Indianapolis, Ind.,
a corporation of Delaware

Application March 17, 1937, Serial No. 68,235

Term of patent 14 years

To all whom it may concern:

Be it known that I, William A. McNaught, a citizen of the United States, residing at Chicago, in the county of Cook and State of Illinois, have invented a new, original, and ornamental Design for an Electric Vibratory Interrupter Device, of which the following is a specification, reference being had to the accompanying drawing, forming part thereof.

Figure 1 is a perspective view of an electric vibratory interrupter device, showing my new design;

Figure 2 is a top view thereof; and
Figure 3 is a side view thereof.

The characteristic feature of the present device resides in the upper end portion.

What is claimed is:

The ornamental design for an electric vibratory interrupter device, substantially as shown and described.

W. A. McNAUGHT.
